DESCRIPTION

U.S. PATENT DOCUMENTS

D. 88,226	11/1932	Gold	.....	D15/90
D. 107,317	12/1937	De Murguiondo	.....	D15/90
D. 202,529	10/1965	Rosebrook	.....	D15/90
D. 202,838	11/1965	Brand	.....	D15/90
D. 244,131	4/1977	Lalonde	.....	D15/90
D. 263,398	3/1982	Tiller	.....	D15/90
D. 318,281	7/1991	McKinlay	.....	D15/90
D. 342,264	12/1993	Pittman	.....	D15/90
2,228,634	1/1941	Lenning	.....	.

FIG. 1 is a top plan view of a novelty ice cube tray showing
my new design;

FIG. 2 is a bottom plan view thereof;

FIG. 3 is a front elevational view with the rear view being
a mirror image thereof;

FIG. 4 is a right side elevational view thereof; and,

FIG. 5 is a left side elevational view thereof.

The broken line showing of the pan in FIGS. 4 and 5 is for
illustrative purposes only and forms no part of the claimed
design.
